GAS BURNER

Filed Oct. 1, 1930

JULIO GONZALEZ
INVENTOR

BY *Victor J. Evans*

ATTORNEY

WITNESS:

UNITED STATES PATENT OFFICE

JULIO GONZALEZ, OF JERSEY CITY, NEW JERSEY

GAS BURNER

Application filed October 1, 1930. Serial No. 485,722.

This invention relates to gas burners and more particularly to a burner for use in firing coal stoves and the like, the principal object of the invention being to provide 5 means for doing away with the necessity of starting a fire with wood or other kindling material.

Another object of the invention is to provide a fire igniting burner which may be inserted 10 in the stove when the fire is to be started and easily removed and placed out of the way thereafter.

Still another object of the invention is to provide means for igniting coal and other 15 solid fuel in a stove speedily and without dirt or labor.

Other objects and advantages of the invention will be hereinafter specifically pointed 20 out, or will become apparent, as the specification proceeds.

With the above indicated objects in view, the invention resides in certain novel constructions and combinations and arrangement of parts, clearly described in the following 25 specification and fully illustrated in the accompanying drawings which latter show embodiments of the invention as at present preferred.

In said drawings:

30 Fig. 1 is a side elevation of a stove, partially in section, showing the method of using the embodiment.

Fig. 2 is a top plan view of the embodiment.

Fig. 3 is a central vertical section of same.

35 Fig. 4 is a section in line 4-4 of Fig. 3.

Fig. 5 is a sectional view of a modification of the embodiment.

Referring now more particularly to said drawings, the embodiment, as at present preferred, includes a burner having a body portion 40 10, a hanger portion 11, integral with said body portion, and a gas connecting portion 12. The embodiment is preferably constructed of cast iron and is detachably mounted 45 between the grates 13 of a stove 14 by means of a spring clip 15, which passes through the hanger portions 11. In order to insert said spring clip between two of said 50 grates it is only necessary to compress the

end portions of said spring clip together, as shown in the dotted lines in Fig. 4.

The body portion 10 is somewhat tapered, the larger end thereof being near the outside of said stove. A narrow rectangular slot 16 55 with flange edges is provided on the upper side of said body portion in order to provide a burner area. The gas connecting portion 12 is constructed with a plurality of ridges 12' in order to provide an airtight engagement with the gas hose 17. This gas connecting portion is also provided with a tapered opening 18, the inner portion 18' being smaller in order to concentrate the gas pressure at this point. A cut away portion 19 of the 60 body portion is provided in order to allow the air to enter and mix with the gas.

When it is desired to start a fire in the stove, the coal is placed upon the grates and the burner is placed underneath same by 70 means of the aforesaid spring clip. The gas is then turned on and the gas ignited with a match. The burner is allowed to burn only long enough to completely ignite the coal. The burner may then be removed, the operator taking care not to burn the hands. The 75 gas hose may then be removed and the burner hung up in any convenient place by means of a looped portion 20, integral with the smaller end of the body portion.

In the modification shown in Fig. 5, the upper portion of the body portion is provided with a solid piece of metal 21, integral therewith, having a hole 21' therethrough. Two pieces of spring metal 23 are secured to said 85 solid piece 21 by means of a bolt 24.

The hereinbefore described construction admits of considerable modification without departing from the invention; therefore, it is the wish not to be limited to the precise 90 arrangements shown and described, which are as aforesaid, by way of illustration merely. In other words the scope of protection contemplated is to be taken solely from the appended claim, interpreted as broadly as is 95 consistent with the prior art.

What is claimed as new is:

In a fire kindler, the combination of a tapered body portion having a longitudinal compartment extending lengthwise of same, a 100

gas connecting portion at the larger end of said body portion and a hanger structure on the upper side of said body portion and being integral therewith, a spring clip through said hanger structure adapted to detachably secure said body portion to the grates of a stove, said body portion having a cut away portion on the underside thereof to admit air into said compartment, a narrow rectangular opening on the upper side of said body portion, said opening adapted to provide a burner portion for said fire kindler, and a hanger structure at the smaller end of said body portion adapted to provide means for hanging said burner when not in use.

In testimony whereof I hereby affix my signature.

JULIO GONZALEZ.
